FIG. 2.

UNITED STATES PATENT OFFICE.

SYLVESTER VOORHIES, OF ENDERLIN, NORTH DAKOTA.

MAIN-LINE TELEGRAPH-REPEATER.

1,277,507.

Specification of Letters Patent.

Patented Sept. 3, 1918.

Application filed January 10, 1917. Serial No. 141,623.

To all whom it may concern:

Be it known that I, SYLVESTER VOORHIES, a citizen of the United States, resident of Enderlin, county of Ransom, State of North Dakota, have invented certain new and useful Improvements in Main-Line Telegraph-Repeaters, of which the following is a specification.

In the operation of a telegraph line, it has been customary to provide the repeater with a local battery, thereby increasing the initial cost and the cost of maintenance of the line.

The object of my present invention is to provide a repeater which will dispense entirely with the use of a local battery and effect a considerable saving in the cost of installation and maintenance of the repeater.

A further object is to provide a repeater having provision for ease of adjustment to compensate for varying climatic conditions.

Other objects of the invention will appear from the following detailed description.

The invention consists generally in a repeater having means for utilizing the main line battery and eliminating entirely the use of a local battery.

In the accompanying drawings forming part of this specification.

Figure 1 is a diagrammatic view illustrating the repeater and circuit when the line is not in use, both east and west line keys being closed. Fig. 2 is a similar view showing the position of the parts when the west line key has been opened, but before the movement of the parts has been completed. Fig. 3 is a similar view showing the final position assumed by the parts when the west line operator has opened his key and before he has begun to telegraph.

In each of the three figures it is assumed that A is connected to a west going line, and A' to an east going line, which lines are controlled by the ordinary type of telegrapher's key.

The repeater may be considered as inserted into the line between these sections and connected therewith at X and X'. Spring circuit closers D and D' are connected at one end through resistance coils C and C' with the main line wires A and A'. Electromagnets I and I' have armatures H and H'. The ends of these armatures extend a sufficient distance to contact with the circuit closers D and D'. Stops S and S' limit the

movement of the armatures away from the cores of the magnets.

Contact points G and G' are provided in the path of the circuit closers D and D' and conductors F and F' are connected with the line wires A and A' and insulated from said circuit closers. The armatures H and H' have springs V and V', which normally tend to hold these armatures out of contact with the cores of the magnets I and I' and away from D and D'. A pair of magnets J and J' are provided, arranged in opposing relation to one another and having an armature L mounted to swing between them through alternate attraction of these magnets. Conductors O and O' connect one side of the magnets J and J' with the contact posts G and G' and similar conductors Z and Z' connect the other side of the magnets J and J' with the contacts E' and E respectively. Spring circuit closers M and M' are positioned upon opposite sides of a T-shaped head L' of the armature L to be engaged thereby for making and breaking the contact between these circuit closers and posts N and N'.

Conductors P and P' and R and R' connect the contacts N and N' with one side of the magnets I and I', and conductors B and B' connect the other side of these magnets with the main line battery and the ground. Conductors W and W' connect the circuit closers M and M' with the circuit closers D' and D and with the line wires A' and A through the coils C' and C, and permanent magnets K and K' are mounted upon opposite sides of the armature L for holding it against the spring contact closers M and M' to keep them out of engagement with the contacts N and N'.

With the circuit and apparatus in the condition as shown in Fig. 1, should the west operator open his key, an actuation of the parts of the repeater is accomplished and the first circuit changes established are as shown in the diagrammatic view illustrated by Fig. 2.

When the circuit of the west line is opened by the west operator's key, the battery which has been energizing the magnet I' is cut off by the opening of the west operator's key, the former holding circuit being as follows:

Battery 1, wires 2, B, magnet winding I', wire R', armature H, to which wire R' is

electrically connected, contact 3, spring D, wire 4, resistance coil C, wires 5 and 6, and out on the conductor A to the west line through the key at that station to ground, 5 and back through the earth to the grounded side of the battery 1.

When the coil I' has been deenergized by the opening of the key, the armature H' is released and the spring V moves the armature over to the stop S' which limits its 10 movement.

The spring D', which is in contact at 7 with the armature H', follows the armature in its backward movement until it is stopped 15 by the stop E', thus opening the contact between the contact member 8, carried by and insulated from the spring D', and the stop G'.

Looking at Fig. 2, it is seen that the contact between the member 8 and the stop G' 20 has been opened, but the contact 7 is still closed and the contact has been closed between the stop E' and the spring D'. This closes a circuit energizing coil J, the circuit 25 actuating the coil J being as follows:

Resistance coil C', wires 9 and F, contact member 11, which is carried by and insulated from the spring D, contact stop G, wire O, coil J, wire Z, contact point E', 30 spring D', wire 12, to the other side of the resistance coil C'.

The two halves of the repeater are exactly the same, and we have seen by tracing out the west line circuit that while the key 35 is closed current flows through the resistance coil C; hence current is now flowing through the resistance coil C' from the east line circuit and part of the current is shunted through the winding J, thus actuating the 40 armature L.

When the armature L is pulled to the left, as shown in Fig. 2, a permanent magnet K serves to hold it in that position until the coil J' has been actuated and the T-shaped head L' of the armature L has moved the 45 spring M to the left so as to break the contact between the spring and the post N and close the contact between the spring M' and the post N'.

60 The contact 3 is then short-circuited by the contact between the post N' and the spring M' over wires P' and W'.

Similarly the contact 7, which is in parallel with the contact between the post N 55 and the spring M, through wires W and P now has its shunt removed so that the actuation of the coils I and I', through the operation of the west line operator's key, can cause no circuit changes dependent upon the 60 contact 3, that contact being shunted as described, but the contact 7 will follow the operator's key and repeat the impulses to the east line.

Looking now at Fig. 3, it will be noted 65 that the contact 7 has been opened and the

coil I will now be deenergized, the former holding circuit being as follows:

Battery 15, wires 16 and B', winding I, wire R, armature H', contact 7, spring D', wire 12, resistance coil C', wires 9 and 19, to 70 the east line through the closed key at that station to the ground, back through the earth to the grounded side of the battery 15.

Hence, while the west operator is telegraphing, and therefore opening and closing 75 his key, both coils I and I' will be actuated, but the contact 3 has been rendered inactive while the contact 7 is active and accomplishes the repeating of the current impulses 80 to the east line.

The main line battery 15 is thus sending out impulses following the west line operator's key through the following circuit:

Wires 16, B', winding I, wire R, armature H', contact 7, spring D', wire 12, resistance coil C', wires 9 and 19, through conductor A' to the east line station. The sequence of operation of the armatures H and H' depends, of course, upon which line key is opened. That is, if a key in section A 90 of the line is opened first, then armature H' will move first, followed by armature H, while if a key in section A is first opened, then armature H will move first, both armatures operating with each opening or 95 closing of a key in either section of the line. The magnet J will be energized first when armature H' moves first and if armature H is moved first, then the magnet J' is energized first. 100

While I have described my invention and illustrated it in one particular design, I do not wish it understood that I limit myself to this construction, as it is evident that the application of my invention may be 105 varied in many ways within the scope of the following claims.

I claim as my invention:

1: A main line telegraph repeater comprising primary magnets in circuit with the 110 main line, armatures for said magnets, circuit closers controlled by the movement of said armatures, secondary magnets in circuit with said main line for receiving a portion of the main line current therefrom, an 115 armature for said secondary magnets, and circuit closers connected with said primary magnets and controlled by the movement of the armature of said secondary magnets for making or breaking the circuit through 120 said primary magnets.

2: A main line telegraph repeater comprising main line magnet coils, armatures co-acting with said coils, a pair of line controller magnet coils, an armature co-acting 125 therewith, contacts controlled by said main line magnet coil armatures, for selecting either of said line controller coils, and holding means associated with said line controller armature for maintaining it in either 130

of two positions, after one of the line controller magnet coils has been energized, until the other of said line controller magnet coils has been energized.

- 5 3. A main line telegraph repeater comprising a pair of main line magnet coils, one in circuit with the east going line, the other in circuit with the west going line, a pair of line controller coils, a resistance 10 coil in circuit with each of said main line magnet coils for shunting a part of the current into said line controller coils, contacts controlled by said main line magnet coils for selecting said line controller coils, and 15 circuits controllable by said main line magnet coils from either the west or the east line for actuating said line controller coils.

4. A main line telegraph repeater comprising a pair of main line magnet coils, an 20 armature associated with each of said magnet coils, an east line circuit including one of said magnet coils and a resistance coil, a west line circuit including the other of said magnet coils and a resistance coil, a 25 pair of line controller coils, an armature controllable by either of said line controller coils, contacts controllable by the armatures of said main line coils for shunting said line controller coils across said resistance 30 coils selectively.

5. A main line telegraph repeater comprising a pair of main line magnet coils, one of said coils being in circuit with a resistance coil and an east going line, the other 35 of said coils being in circuit with a second resistance coil and a west going line, a pair of line controller coils, said resistance coils shunting a portion of the current through 40 said line controller coils, a circuit and contacts controllable through the operation of the east line circuit for actuating one of said line controller coils and rendering inactive the other of said line controller coils, a second circuit and contacts under control of 45 said west line circuit controlling the other of said line controller coils and rendering said first line controller coil inactive, an armature associated with said line controller coils and controllable by either of said coils,

and means associated with said armature 50 for holding said armature in either of two positions in which it is drawn by one of said line controller coils until it is actuated by the other of said line controller coils.

6. A main line telegraph repeater comprising main line magnet coils, armatures and contacts co-acting with said coils, a pair of line controller magnet coils, an armature co-acting therewith, a circuit co-acting with 55 said main line magnet coils and said line controller magnet coils and including two resistance coils, said circuit including contacts for actuating one of said line controller magnet coils on the opening of one end of the main line in which the repeater is 60 connected and also contacts for actuating the other of said line controller magnet coils when the other end of the main line in which said repeater is connected is opened, said controller magnet coils being actuated 65 by being bridged across said resistance coils.

7. In a main line telegraph repeater the combination of a line controlled magnet coil, an armature and contacts controlled by said coil and a main line magnet coil, 70 an armature associated therewith, a pair of springs positioned adjacent to said main line coil, the forward of said springs carrying a contact and the rearward of said springs carrying two contacts, a contact on 75 said armature adapted to make contact with one of said contacts on said rearward springs, a back contact adapted to make contact with the second of said contacts on said rearward spring and a circuit associated 80 with said coils and said contacts for energizing said line controller coil on the first closing of said contact between said rearward spring and said back contact whenever a main line operator takes control of 85 the line.

In witness whereof, I have hereunto set my hand this 28 day of Dec., 1916.

SYLVESTER VOORHIES.
